UNITED STATES PATENT OFFICE

CIPRIANO ANDRADE, JR., OF NEW YORK, N. Y.

DIFFERENTIAL

Application filed December 22, 1928. Serial No. 327,884.

My invention relates to differentials; and the object of my invention is to create a roller locking differential to eliminate backlash and also to prevent the driven members and 5 also to prevent the locking rollers from moving outward even when the outside holders on the two driven members become loose.

I attain these objects by the mechanism illustrated in the accompanying drawings, in 10 which :

Fig. 1 is a sectional side view of my device; Fig. 2 is an end view of a portion of the middle of my device; Fig. 3 is a left hand end view of my device with B^5 removed; and 15 Fig. 4 is a left hand end view of my device with the left hand end flange F^2 removed, to show the interior arrangement, and the circular solid ring W not shown therein.

Similar letters and numerals refer to similar parts throughout the several views:

A is the driving member; A^2 are the eccentric arcs, being the locking surfaces on the inner face of driving member A ; B is the right hand driven member; B^1 is the locking 25 surface of driven member B ; B^2 is the locking surface of driven member B^3 ; B^3 is the left hand driven member; B^4 is a circular outside holder on B , to be attached in any appropriate manner to the rear axle housing; 30 B^5 is a circular outside holder on B^3 , to be attached in any appropriate manner to the rear axle housing; B^{10} is a circular element to hold B and B^3 from moving against each other radially; B^{11} are the keyways to hold 35 the keys for the axle end on B ; B^{12} are the keyways to hold the keys for the axle end on B^3 ; C are the right hand end locking rollers; C^3 are the left hand end locking rollers; D are the control rods; E is a circular element 40 to hold the master gear M ; F is the right hand end flange fastened to A ; F^2 is the left hand end flange fastened to A ; F^{10} are the bolts to hold F to A ; F^{11} are the bolts to hold F^2 to A , and to M , and to E ; and W is the 45 circular solid ring between the locking rollers C and the other locking rollers C^3 , and over the small ends of control rods D .

The circular solid ring W is fully stated in my patent application Serial No. 76,843; 50 the object being to keep the locking rollers

C from touching the locking rollers C^3 ; and also to hold the locking rollers C and C^3 always in contact with the locking surfaces B^1 and B^2 , through the control rods D .

By reference to Figs. 1 and 2 of my issued 55 Patent No. 1,546,460, it will be noted that the locking rollers need not necessarily be in direct contact with one another. And therefore in my claims herein, when I use the term "locking rollers", this will cover either a set 60 of locking rollers in contact with each other as shown in Fig. 4 herein, or a set of locking rollers not in contact with each other, as shown for example in my said issued Patent No. 1,546,460 or any mechanical equivalent 65 thereof.

It will be understood that the control rod D might be made with its large end integral with a solid locking roller and with its small end fitting into the other locking roller with 70 an opening, as fully disclosed in my issued Patent No. 1,505,124.

It will be understood that instead of the master gear M being fastened sideways on the left hand end of the driving member A , 75 said master gear M might be fastened sideways on the right hand end of the driving member A , as is well known in some of the Mack trucks. Also said master gear M might be fastened on the middle of the driving member A or made a part of driving member A , and fastened downward instead of sideways, as is well known in some of the other well known trucks and cars. As is well known in the art the master gear can be 80 put at any position desired.

The operation of my device is as follows:

The differential functioning of the locking rollers and control rods is fully described in my issued Patents No. 1,471,642; No. 90 1,505,124 and No. 1,505,687. And the elimination of backlash is fully described in my patent application Serial No. 138,157.

In my present device herein, the end flanges F and F^2 are not to have any washers on 95 their outside, as for example in the old type Ford car. In other words, said end flanges F and F^2 are not to have anything whatever to touch their outside surface, or their middle circular opening; the purpose of this being 100

that said end flanges F and F² must not have anything to prevent the driving member A from having free radial movement so as to come instantly into locking contact with the locking rollers C or C³, or both C and C³. And the inside part of said end flanges F and F² are to have always a clearance of at least a few thousandths of an inch between the ends of locking rollers C and C³, and also between the ends of driven members B and B³; and that again always makes said end flanges F and F² to allow the driving member A to have free radial movement so as to come instantly into locking contact with the locking rollers C or C³, or both C and C³. And the outside holders B⁴ and B⁵, being properly attached to the rear axle housing, will hold said driven members B and B³ from moving outward or radially; but will permit B and B³ to rotate. And the circular element B¹⁰ will prevent the driven members B and B³ from moving against each other radially, but will permit B and B³ to rotate past each other. Of course later on, after the car has been in long use, the outside holders B⁴ and B⁵ will have their connections with the rear axle housing somewhat loose, and in that event in my patent application Serial No. 138,157 the two driven members and the two sets of locking rollers therein will begin to move outward, but in my present application herein, the end flanges F and F² fastened to A herein will prevent the driven members B and B³, and the two sets of locking rollers C and C³, from moving outward. And also in my present application herein, these end flanges F and F² being fastened to driving member A, makes it very easy to assemble this differential in the rear axle housing, because none of the parts can fall out. But in the form of my other patent application Serial No. 138,157, when it is to be assembled in the rear axle housing, the driven members and the locking rollers therein can fall out unless the driven members are held by hand to keep from falling out, until they are fully covered by the various parts in the rear axle housing.

It will be noted in all of my previous patents and patent applications, and in the entire prior art, that there has never been two end flanges fastened tightly to the driving member, without anything to touch the outside surface or the middle circular opening of said end flanges, and on the inside of said two end flanges two driven members having each an outside holder to make each driven member held in exact position with the rear axle housing, and also to hold each driven member from radial movement.

And by leaving the end flanges F and F² herein entirely radially clear as previously stated and shown herein, at least one locking roller on each driven member at all times is in direct contact with the locking surface of the driving member and the locking surface

of the driven member, even when the locking roller is in neutral position at the centre of the eccentric arc of the driving member. And if even one locking roller is thus in direct contact with the driving member and a driven member, backlash and slippage becomes impossible, because the moment the driving member starts to rotate faster than the driven member the locking roller locks at the locking point of the eccentric arc, and all the other locking rollers on that driven member are thus forced to lock also.

I claim:

1. In a differential; a first set of locking rollers; a second set of locking rollers; a driving member having locking surfaces outside of said locking rollers; a first driven member having locking surface inside of said first set of locking rollers; a second driven member having locking surface inside of said second set of locking rollers; a first end flange fastened on one side of said driving member, said first end flange being on the outside of said first driven member, and on the outside of said first set of locking rollers, said first end flange having nothing whatever to touch its outer surface or its middle circular opening, said first end flange being free for radial movement against said first driven member and also against said first set of locking rollers; and a second end flange fastened on the other side of said driving member, said second end flange being on the outside of said second driven member, and on the outside of said second set of locking rollers, said second end flange having nothing whatever to touch its outer surface or its middle circular opening, said second end flange being free for radial movement against said second driven member and also against said second set of locking rollers; said driving member being free for radial movement except by actual pressure contact of one or more of said locking rollers against said driving member and against one or both of said driven members.

2. In a differential; a first set of locking rollers; a second set of locking rollers; a driving member having locking surfaces outside of said locking rollers; a first driven member having locking surface inside of said first set of locking rollers; a second driven member having locking surface inside of said second set of locking rollers; said two driven members having their middle ends in contact with each other and rotatable one against the other; a circular element to hold said first driven member and said second driven member from moving against each other radially; a first end flange fastened on one side of said driving member, said first end flange being on the outside of said first driven member and on the outside of said first set of locking rollers, said first end flange having nothing whatever to touch its outer surface or its middle circular opening, said first end flange being free

for radial movement against said first driven member and also against said first set of locking rollers; and a second end flange fastened on the other side of said driving member, said second end flange being on the outside of said second driven member, and on the outside of said second set of locking rollers, said second end flange having nothing whatever to touch its outer surface or its middle circular opening, said second end flange being free for radial movement against said second driven member and also against said second set of locking rollers; said driving member being free for radial movement except by actual pressure contact of one or more of said locking rollers against said driving member and against one or both of said driven members.

3. In a differential; a first set of locking rollers; a second set of locking rollers; a driving member having locking surfaces outside of said locking rollers; a first driven member having locking surface inside of said first set of locking rollers; a first outside holder to hold said first driven member in connection with the rear axle housing; a second driven member having locking surface inside of said second set of locking rollers; a second outside holder to hold said second driven member in connection with the rear axle housing; a first end flange fastened on one side of said driving member, said first end flange being on the outside of said first driven member, and on the outside of said first set of locking rollers, said first end flange having nothing whatever to touch its outer surface or its middle circular opening, said first end flange being free for radial movement against said first driven member and also against said first set of locking rollers; and a second end flange fastened on the other side of said driving member, said second end flange being on the outside of said second driven member, and on the outside of said second set of locking rollers, said second end flange having nothing whatever to touch its outer surface or its middle circular opening, said second end flange being free for radial movement against said second driven member and also against said second set of locking rollers; said driving member being free for radial movement except by actual pressure contact of one or more of said locking rollers against said driving member and against one or both of said driven members.

4. In a differential; a first set of locking rollers; a second set of locking rollers; a driving member having locking surfaces outside of said locking rollers; a first driven member having locking surface inside of said first set of locking rollers; a second driven member having locking surface inside of said second set of locking rollers; a first end flange fastened on one side of said driving member, said first end flange being free for radial movement against said first driven member and also against said first set of locking

rollers; and a second end flange fastened on the other side of said driving member, said second end flange being free for radial movement against said second driven member and also against said second set of locking rollers; said driving member being free for radial movement except by actual pressure contact of one or more of said locking rollers against said driving member and against one or both of said driven members.
